Attorney

UNITED STATES PATENT OFFICE

MARINUS TINGLEFF, OF SANDPOINT, IDAHO

LIQUID SAMPLING INSTRUMENT

Application filed June 15, 1931. Serial No. 544,504.

My present invention relates to improvements in liquid sampling instruments or blood-extracting devices, designed to withdraw blood, by pressure from within the body, and while the device or instrument is adapted for various purposes, it is especially designed for extracting samples of blood from cattle and live-stock, for testing in the laboratory. In the process or operation of extracting the sample from the animal, the animal frequently becomes obstreperous, resulting in breaking of the bottle or receptacle and consequent loss of the sample. The primary object of my invention is the provision of a casing or holder for the receptacle, which shields and protects the receptacle, and which holder forms the support for the hypodermic needle. Thus the instrument comprises essentially three separable elements, the bottle or receptacle, the holder, and the hypodermic needle, and these elements may be separated when desired or necessary, for cleansing, to insure sanitary condition of the device.

The invention consists in certain novel combinations and arrangements of parts involving the bottle, holder and needle, as will hereinafter be more fully set forth and claimed. In the accompanying drawing I have illustrated one complete example of the physical embodiment of invention wherein the parts are combined and arranged according to one mode I have thus far devised for the practical application of the principles of my invention.

Figure 1 is a perspective view of the instrument in closed position. Figure 2 is a view of the device showing the cap removed, but with the needle in inverted position, while Figure 3 is a similar view with the needle in extended position and ready for use.

Figure 4 is a view of the holder showing the snap-catch or detent for retaining the bottle or receptacle in the holder.

Figure 5 is an enlarged sectional view of the holder, showing the bottle in dotted lines and retained therein, at line 5—5 Fig. 4.

Figure 6 is a detail view of the hypodermic needle, detached.

Figure 7 is a perspective view of the closed head of the holder, as at line 7—7 of Figure 4.

Figure 8 is an enlarged detail view of the

head portion of the holder showing the neck of the bottle and the vent ports.

The bottle or receptacle 1 may be of any usual form, but is here shown as cylindrical, and provided, just below its open mouth, with 55 an exterior, annular groove 2 encircling the neck of the bottle.

The mouth-end of the bottle is slipped into the open end of a cylindrical holder or casing 3 fashioned of suitable material, and the open 60 end of the holder is slotted to form a blade 4 having at its free end or edge a snap catch 4' that projects inwardly of the holder and is adapted to fit snugly up against the bottom edge of the bottle, as indicated in Figure 5. 65 The blade 4 is preferably integral with the holder, and is of resilient material in order that the bottle may be slipped into the open end of the holder, (by pressing outwardly the snap-catch 4') and after the bottle is properly 70 enclosed in the holder, the snap-catch holds the mouth of the bottle in close contact with the under face of the head 6 that closes the upper end of the holder.

In its side walls the holder is provided with 75 one or more windows or slots 5 that terminate near the ends of the holder, and permit inspection of the contents of the bottle while in the holder. These windows also provide for ingress of the thumb or finger, which are 80 pushed into the annular groove 2 of the bottle as a finger-hold.

Thus upon inspection of Figure 8 it will be apparent that the finger nail or thumb nail may be inserted in one of the windows and 85 pressed against the annular groove 2, and then by pressure, the bottle may be slipped out of its holder, past the snap-catch 4', without danger of spilling its contents.

The underside of the fixed head 6, as seen 90 in Figures 7 and 8 is corrugated at 7 to form radial ports, and as the mouth of the bottle fits snugly against the underside of underface of the head, these ports form vents to the atmosphere from the bottle whereby blood pressure within the body of the animal will operate to force blood through a hypodermic needle 8, when the latter is supported in correct position in the head 6.

The needle is tubular as usual and provid-

ed with the customary point 9 that is jabbed or inserted into the body of the animal, for the extraction of the blood sample.

The head 6 of the holder 3 is fashioned with an externally threaded boss 10, an orifice 11 and an internally threaded part or socket 12, the latter for the reception of complementary parts on the needle.

As best seen in Figure 6 the needle is equipped with a plug or stopper 13 secured thereon in suitable manner, and the ends 14 and 15 of this stopper are threaded for alternate or selective use with the threaded socket 12 of the holder. In Figure 2 the threaded end 15 of the stopper is screwed into the socket to hold the needle in inverted position within the holder or its contained bottle, while in Figure 3 the threaded end 14 is screwed into the socket 12 with the needle in operative position for use.

A cap 16 is provided with interior threads that screw down on the exterior threads of the boss 10 to protect or shield the needle when in position of Figure 2.

Having thus fully described my invention, what I claim as new and desire to secure by Letters Patent is:—

1. The combination of a bottle holder adapted to receive a bottle and having a head at one end, a removable, tubular needle mounted in the head and projecting into the holder, means for retaining an open-mouth bottle against the inner face of said head, and said inner face having vent grooves therein for venting the interior of the bottle.

2. The combination of a bottle holder open at one end, a head at the other end of the holder, a removable, tubular needle mounted in the head and projecting into the holder, an integral resilient snap spring within the open end of the holder for retaining the open mouth of a bottle against said head, and said head having vent grooves in its inner face to vent the interior of the bottle.

45 In testimony whereof I affix my signature.
MARINUS TINGLEFF.
